United States Patent Office.

TIMOTHY S. THORN, OF SOUTH AMBOY, NEW JERSEY.

Letters Patent No. 75,816, dated March 10, 1868.

IMPROVEMENT IN FOLDING FANS.

The Schedule referred to in these Letters Patent and making part of the same.

TO ALL WHOM IT MAY CONCERN:

Be it known that I, TIMOTHY S. THORN, of South Amboy, in the county of Middlesex, and State of New Jersey, have invented certain new and useful Improvements in Fans; and I do hereby declare that the following is a full, clear, and exact description thereof, reference being had to the accompanying drawings, and to the letters of reference marked thereon.

The object of my invention is the production of a fan which will fold up into a very small compass, and so constructed as to be strong, durable, neat, and elegant in appearance, and effective in its operation. It consists of a series of radial ribs, hung on a pin at the centre of the fan, and so connected and arranged that they may readily be spread out, so as to resemble the spokes of a wheel, and as readily brought together, so that the whole shall occupy but little more space than one of the leaves of the fan, as hereinafter set forth; also, in the combination, with the leaves of the fan, of a handle, and a fastening or stay therefor, so constructed that the said handle can be readily folded up, and also made very firm and secure when opened out to prepare the fan for use, substantially as hereinafter set forth. In the accompanying drawings—

Figure 1 is a side view of my improved fan opened out ready for use.

Figure 2 is a vertical central or axial section thereof through the centre of the handle.

Figure 3 is a cross-section of the joint and fastening, at the junction of the ribs and the handle.

Figure 4 is a side view of the fan folded up, and having a red line circumscribed about it to indicate the size of a box in which it could be made to fit.

A A are the leaves of the fan, the ribs being shown in the dotted lines at B B. Two strong ribs, C C', are put on outside of the others, and somewhat longer, which form a part of the handle when the fan is opened, and which hold the rest of the ribs and the leaves in place at all times. All these ribs are hung on a pin, a, in the centre of the fan, and a pin, b, is set firmly into the rib C, and another pin, c, in the rib C', by which pins the opening and closing of the leaves of the fan is secured. The leaves are made to occupy positions at equal distance from centre to centre, by means of thread-stays of suitable length, in the usual manner. The rib C, at its outer end, is formed into a cylinder, e, which makes a part of the joint. The handle D is fastened to the piece e by means of the link E, which is secured to the piece e by the pin f, and to the handle by the pin g, in such a manner that the handle may be readily swung around parallel with the ribs C C', when the fan is closed. F is a small clasp hinged to the rib C', at its outer end. On the inner side of this hinged clasp is a hook, h, which locks under or into another hook or recess in the piece e, and also a pin, i, which enters a hole in the piece e. This pin i has grooves in its side, as seen in fig. 3. On the handle D is a sliding ferrule, which slides over the joint at the junction of the piece e and handle D, when the handle is straightened out radially from the centre of the fan, and holds the said handle firm and stiff. In one side of the ferrule G is a tapering slot, j, which allows the ferrule to be pushed up past the pin i, the sides of the said slot entering the grooves in the pin i, thereby preventing said pin from backing out of the hole in the piece e, and firmly securing the ribs B, C, and C', the handle D, and the hinged clasp F in place. A portion of the ferrule G is enlarged or made thicker, to give it additional strength and stiffness, as seen at k.

The fan constructed as described possesses the advantages of great strength and durability, increased portability, and it is capable of being manufactured in forms of great elegance.

Having thus fully described my invention, I claim—

1. The combination, with the ribs B, C, and C', and handle D, of the ferrule G, substantially as and for the purpose set forth.
2. The combination, with the ribs C and C', of the clasp F, ferrule G, and handle D, substantially as and for the purpose set forth.

TIMOTHY S. THORN.
